CLAIM

We claim the ornamental design for a lid, as shown and described.

DESCRIPTION

FIG. 1 is a top perspective view of our new design for a lid, shown with an environmental cup for clarity of disclosure;

FIG. 2 is a rear elevation view of our new design for a lid, shown with no cup for clarity of disclosure;

FIG. 3 is a front elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is cross-sectional view thereof taken about line 8-8 of FIG. 6.

The broken line showing of a cup in FIG. 1 depicts environment and forms no part of the claimed design. The broken line arrows in FIG. 6 depict cross-sectional view indicia and form no part of the claimed design.
